BENJIMAN F. SUMPTER, OF WICHITA FALLS, TEXAS; DOUGLAS E. WINFREE, OF CHICKASHA, OKLAHOMA; AND ROLAND B. ROBIRDS, OF WICHITA FALLS, TEXAS.

OIL-WELL DERRICK.

Application filed April 1, 1927. Serial No. 180,280.

This invention relates to oil well derricks, and particularly to connections for sectional corner posts and anchorages for the girths of the derricks, and the invention 5 further contemplates the provision of novel brace rod adjusting and connecting means to be associated with the corner post joints.

It is a further object of this invention to provide anchors for the corner posts that 10 are comparatively inexpensive, as well as strong and durable.

With the foregoing and other objects in view, the invention consists in the details of construction and in the arrangement and 15 combination of parts to be hereinafter more fully set forth and claimed.

In describing the invention in detail, reference will be had to the accompanying drawings forming part of this application 20 wherein like characters denote corresponding parts in the several views, and in which—

Figure 1 illustrates a view in elevation of a fragment of a derrick;

25 Figure 2 illustrates an enlarged sectional view on the line 2—2 of Fig. 1;

Figure 3 illustrates a detail view of the brace connecting and adjusting means;

Figure 4 illustrates a view in elevation of 30 a corner post anchor;

Figure 5 illustrates a sectional view of a corner post with a derrick reinforcing instrumentation;

Figure 6 illustrates a view in elevation 35 of a modified corner post anchor;

Figure 7 illustrates a perspective view of the inner side of the corner post joint;

Figure 8 illustrates a perspective view 40 thereof from another angle;

Figure 9 illustrates a top plan view of a joint for round corner posts;

Figure 10 illustrates a view in elevation 45 thereof; and

Figure 11 illustrates a plan view of the corner post anchor shown in Fig. 6.

In these drawings, 10 denotes a square corner post to be employed in a derrick structure, the same being anchored on a plate 11 having an upwardly extending lug 12 50 through which a fastening 13, such as a bolt extends for securing the corner post to the anchor. The plate also has flanges such as 14 and a fastening 15 extends through them and through the corner post for further 55 anchoring the corner post to the plate.

Derricks are usually constructed by employing a plurality of sections for each corner post and the sections are connected together in different ways.

There is illustrated herein a joint or corner bracket for a square post which comprises a tubular section 16 which is square in cross section or of a shape to receive and conform to the contour of the post sections which are to be lodged in the bracket. 60 Flanges 17 and 18 are formed as parts of the bracket, and the flanges are provided with apertures 19 to receive hooks 20 of the brace rods 21 by which the said brace rods are connected to the corner brackets. 65

Girth shoes 22 by which the ends of the girths 23 may be lodged are also included in the structure of the bracket and a diagonally disposed web 24 is also rigid with the bracket structure, and, in the present embodiment of the invention, these webs constitute anchorages for reinforcing posts 25. The webs are slotted, as shown at 26, and these slots are intended to receive bolts 27 whose heads 28 engage the inner surfaces of 70 the webs and whose outer ends project through a clamping plate 29 which bears against the side of the reinforcing post or leg opposite that engaged by the web. In the use of oil well derricks, it is usually nec-

essary to build the derrick rigid and strong for use during the drilling operation, whereas for use in pumping, bailing and other operations, the derrick structure need not possess the same degree of strength. By reason 75 of the fact that applicants have provided means for producing a strong and reinforced structure, the derrick may be built to withstand strain incident to the drilling operations, permitting the removal of the reinforcing parts of the derrick in order that they may be again used on other derricks during the drilling operations. This results in a material reduction in cost, since the reinforcing structure can be expeditiously applied to and removed from derricks, as need develops. 80

The form of the invention shown in Figs. 9 and 10 is substantially the same as that disclosed in Figs. 7 and 8, except that the 85 brackets of Figs. 9 and 10 are intended to be used in association with round posts and round girths. As shown in Figs. 9 and 10, the post receiving apertures 30 are round and the girth shoes 31 and 32 are also round, 90

but obviously could be shaped similar to the shoes 22 for use in association with girths that are angular in cross section, and so the inventors do not wish to be limited 5 with respect to these exact structural features. The web 33 has recesses 34 and 35 to be used for assembling a supplemental or reinforcing frame with the main derrick. The stay or bracing rods 21 are here shown 10 as connected to the wings 36 of nuts 37, the nuts for the opposed stay rods being located in spaced relation to each other to engage the double bolts 38 which are threaded in the nuts and the enlarged portion 39 between 15 the bolts may have apertures such as 40 to receive an implement for rotating the bolts when the tension of the rods is to be regulated or adjusted.

We claim:

20 1. In an oil well derrick, a plurality of

brackets adapted to receive the ends of derrick posts, girth shoes carried by the said brackets, a web connecting the shoes, said web having seats in its edge, bolts lying in the recesses with their heads engaging the 25 inner surface of the web, a reinforcing element engaging the outer surface of the web between the bolts, and a clamping plate on the said bolts engaging the surface of the reinforcing element remote from the web. 30

2. In an oil well derrick, a plurality of brackets adapted to receive sectional corner posts, girth shoes carried by each bracket, a web connecting the shoes of each bracket, and a reinforcement clamp anchored to said 35 web.
